No. 37,442.

Patented May 23, 1905.

UNITED STATES PATENT OFFICE.

ALBERT STEFFIN, OF NEW BEDFORD, MASSACHUSETTS, ASSIGNOR TO THE PAIRPOINT CORPORATION, OF NEW BEDFORD, MASSACHUSETTS.

DESIGN FOR A BAS-RELIEF BORDER FOR METALLIC TABLEWARE.

SPECIFICATION forming part of Design No. 37,442, dated May 23, 1905.

Application filed January 14, 1905, Serial No. 241,113. Term of patent 7 years.

To all whom it may concern:

Be it known that I, ALBERT STEFFIN, a citizen of the United States, residing at New Bedford, in the county of Bristol and State of Massachusetts, have invented a new, original, and ornamental Design for Bas-Relief Borders for Metallic Tableware or Similar Articles, of which the following is a specification, reference being had to the accompanying drawing,

10 forming part thereof.

The figure is a section of a border for use

upon any suitable article of metallic tableware, or similar articles, showing my new design.

I claim—

The ornamental design for a bas-relief border for metallic tableware, or similar articles, as shown.

ALBERT STEFFIN.
